UNITED STATES PATENT OFFICE.

DAVID H. WATTS, OF PHILADELPHIA, PENNSYLVANIA.

DESIGN FOR A LAMP.

SPECIFICATION forming part of Design No. 24,738, dated October 8, 1895.

Application filed September 4, 1895. Serial No. 561,467. Term of patent 14 years.

To all whom it may concern:

Be it known that I, DAVID H. WATTS, a citizen of the United States, residing in Philadelphia, Pennsylvania, have invented a new and original Design for Lamps, of which the following is a specification.

My design for a lamp-body is fully illustrated in the accompanying drawings, in which—

10 Figure 1 is a perspective view of the lamp-body. Fig. 2 is a front view, and Fig. 3 is a side view.

15 The essential features of the design are the arrangement of the circular center portion, the flat depending portion, and the hood-section.

A is the center portion, circular in form and having a lens a in front and side lights a' a' at each side.

20 B is a quadrangular hood, elongated trans-

versely and having heads b b at front and back, and depending from the circular center portion is a portion D, flattened transversely and having a rounded lower edge. The portion D has rounded enlargements d d at front and back directly under the circular portion A of the body, and depending from the body are tubular projections e, the whole giving the effect clearly shown in the drawings.

I claim—

30 The design for a lamp body as shown and described in the accompanying drawings.

In testimony whereof I have signed my name to this specification in the presence of two subscribing witnesses.

DAVID H. WATTS.
